MITTEN

Jonathan Winson, Bronx, N. Y., assignor to Air Baby, Inc., New York, N. Y., a corporation of New York

Application November 28, 1956, Serial No. 43,979

Term of patent 14 years

(Cl. D3—11)

Fig. 1 is a plan view of the front of a mitten, showing my new design; the ends of the fingers portion and the thumb being solid color and the body portion being lined to indicate contrast;

Fig. 2 is a side elevational view thereof; and

Fig. 3 is a plan view of the back thereof.

The essential features of my design reside in the portions shown in solid lines on the drawing.

This application is a continuation-in-part of my application for Waterproof Mitten, Serial No. D. 42,093, filed June 29, 1956, and now abandoned.

I claim:

The ornamental design for a mitten, substantially as shown and described.
